GARMENT

Filed March 30, 1925

FIG. 5 BY *Martha Fern Dodge*
Marks & Chaffey ATTORNEYS.

INVENTOR.

UNITED STATES PATENT OFFICE.

MARTHA FERN DODGE, OF WINFIELD, KANSAS.

GARMENT.

Application filed March 30, 1925. Serial No. 19,425.

This invention relates to undergarments or so-called slips, and the object of the invention is to produce a slip which will conform to the configuration of the wearer at the shoulders and hang straight from the shoulders to the bottom in order that it will be adapted for use under the present straight line gowns.

Another object of this invention is to produce a slip of the character indicated, especially adapted for stout figures to produce the result indicated, while providing expandable or yieldable sections for fullness in walking and sitting.

It is a further object of this invention to produce a costume slip of the character indicated which is preferably formed by employing two lengths of material, connected together by seams rearwardly of the sides in order to eliminate bulkiness under the arms, the said seams being associated with pleats below the waistline.

It is a still further object of this invention to produce a slip of the character indicated which can be expeditiously manufactured at comparatively small cost.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of the front of the slip;

Figure 2 illustrates a similar view of the side thereof;

Figure 3 illustrates a similar view of the rear thereof;

Figure 4 illustrates a sectional view on the line 4—4 of Fig. 2; and

Figure 5 illustrates a detail view of a fragment of the slip showing the formation of the seam and pleat on the inside of the garment.

In these drawings, 10 denotes the front of the garment which is formed of one piece of material extending partially around the sides to the seam 11, at which seam the back 12 is joined to the front. The slip is provided with armholes 13 and portions 14 which extend to the shoulder seams 15 where

the front is joined to the back. A dart 16 extends from each shoulder downwardly to near the waistline of the garment and the said dart tapers from the top to the waistline to cause the slip to conform to the figure of the wearer. The dart is relatively wide at the top, approximating an inch in width, although the inventor does not wish to be limited with respect to proportions, as they will vary for garments of different sizes. The term "dart" is herein used to define the parts 16 and 17 as that term is used by the trade. Technically the parts 16 and 17 are what may be termed "tapering tucks."

A horizontally disposed dart 17 is formed in the garment under the armholes and this dart flares from the dart 16 to the seam 11, it being understood that one dart is provided on each side of the garment. The formation of the dart in the manner indicated tends to raise the sides toward the back and causes the sides to hang straight and eliminates wrinkling of the garment under the arms. The darts 17 will be found especially desirable in fitting the garment to stout figures, as it is well known that persons of such figures have an excessive amount of flesh at this point, especially where a stay is worn, and unless a dart were formed, the garment would wrinkle at the armhole and would also sag toward the back. The formation of the dart obviates this undesirable feature and results in a perfectly fitting garment. The darts may be made smaller or larger according to the requirements in practice. The darts 17 also act to connect the front darts 16 with the back pleats of the garment, resulting in a correct fit of the said garment. The concealed outlines of the darts are shown in dotted lines in the drawing being denoted by the numerals 16 and 17.

The material of the back of the garment is wider below the waistline than it is above the waistline and the side portion has pleats 18 and 19 at its edges, the said pleats being formed by turning the material inwardly at the edges, and the said edges are secured to the front at the seams 20.

The hem 21 may be of any appropriate width, and the seams 20 have notches 22 at the junction of said seams and the hem or facing thereof. In order to help hold the hem in place and to support the back, the garment is provided with horizontally dis-

- posed seams 23 which extend from the junction of the seams 11 and 20 toward the back, and the length of the seams 23 is approximately equal to the depth of the pleats, the 5 relation of the seam 23 to the fold of the pleat being shown in Fig. 5 where the arrow A is intended to illustrate the position of the fold of the pleat and in which the seam on the inner side of the garment is depicted. 10 The seam 23 also results in a smoother fitting of the garment, as well as preventing sagging or dipping of the garment at the lower edge of the pleats 18 and 19 and this also tends to hold the hem 21 or the bottom 15 of the garment in position or approximately horizontal. Obviously if the seams 23 were not present, the lower edge of the garment would sag by the pleat dragging down and showing below the edge of the garment. 20 A slip made in accordance with this invention has been found to possess advantages in that relatively stout persons may wear it without causing the garment to bulge under the arms or elsewhere, and the 25 slip under such conditions hangs with its sides straight from top to bottom, whereas the fullness below the waistline affords room while the wearer is walking or sitting.
- In some instances, it may be desirable to 30 make the garment with the so-called camisole top, in which event, the garment will be cut on the dotted line 24 and finished with shoulder straps and binding in the usual fashion.
- 35 I claim:
1. An undergarment having a front length of a width which will extend past the sides of the wearer and a back width filling the space between the edges of the front width, 40 horizontally disposed darts below the arms location of the garment, and vertically disposed darts at the sides of the garment in the front tapering from the shoulders to the waistline portion of the garment.
- 45 2. An undergarment having a front length of a width which will extend past the sides of the wearer and a back width filling the space between the edges of the front width, 50 horizontally disposed darts below the arms location of the garment, said darts being flared from the front toward the rear, and vertically disposed darts at the sides of the garment in the front tapering from the shoulders to the waistline portion of the garment.
- 55 3. An undergarment having a front length of a width which will extend past the sides of the wearer and a back width filling the space between the edges of the front width, 60 horizontally disposed darts below the arms location of the garment, said darts being flared from the front toward the rear, vertically disposed darts at the sides of the garment in the front tapering from the shoulders to the waistline portion of the garment, and pleats in the rear length approximately between the waistline and the bottom of the garment. 65
4. In a garment of the character described, 70 a front width extending from the shoulders to the bottom and having its vertical edges terminating rearwardly of the sides of the garment, darts in the front length tapering from the shoulder to approximately the 75 waistline, darts extending horizontally under the arms location of the garment, the said darts flaring from the front toward the rear, a back length having its edges secured to the edges of the front length, the 80 said back length being wider from the waistline to the bottom than from the waistline to the top, the said wide portion of the back length being shaped to form pleats at the seam where it is connected to the front 85 length, and seams extending horizontally at approximately the waistline from the last mentioned seams toward the back of the garment, the said seams being approximately equal in length to the width of the 90 pleats.
5. In a garment of the character described, 95 a front width extending from the shoulders to the bottom and having its vertical edges terminating rearwardly of the sides of the garment, darts in the front length tapering from the shoulder to approximately the 100 waistline, darts extending horizontally under the arms location of the garment, the said darts flaring from the front toward the rear, a back length having its edges secured to the edges of the front length, the said back length being wider from the waistline to the bottom than from the waistline to the top, the said wide portion of the back length being shaped to form pleats at the seam where it is connected to the front 105 length, seams extending horizontally at approximately the waistline from the last mentioned seams toward the back of the garment, the said seams being approximately equal in length to the width of the pleats, and a hem at the bottom of the garment, the said seams connecting the front and back lengths being notched at the junction of the said seams and the hem. 110
